WATER BUBLER

Roger F. Chapin, Jr., Columbus, Ohio, assignor to Westinghouse Electric Corporation, a corporation of Pennsylvania

Filed Aug. 27, 1965, Ser. No. 86,740

Term of patent 14 years

(Cl. D91—4)

FIGURE 1 is an isometric view of a water bubbler embodying my invention;

FIG. 2 is a plan view of the top thereof;

FIG. 3 is an end elevational view taken from the left of FIG. 2;

FIG. 4 is a front elevational view;

FIG. 5 is an end elevational view taken from the right of FIG. 2; and

FIG. 6 is a plan view of the bottom.

The rear side, that is, the side opposite to the side shown in FIG. 4, is substantially the same in appearance as the side shown in FIG. 4.

The dominant features of my design reside in the parts shown in the full lines.

What I claim is:

The ornamental design for a water bubbler, substantially as shown and described.
